UNITED STATES PATENT OFFICE.

SVERRE SVENDSGAARD, OF SVERRE, MINNESOTA.

MIRROR-BRACKET.

SPECIFICATION forming part of Letters Patent No. 699,901, dated May 13, 1902.

Application filed July 5, 1901. Serial No. 67,220. (No model.)

To all whom it may concern:

Be it known that I, SVERRE SVENDSGAARD, a citizen of the United States, residing at Sverre, in the county of Ottertail and State 5 of Minnesota, have invented certain new and useful Improvements in Mirror-Brackets; and I do hereby declare the following to be a full, clear, and exact description of the invention, such as will enable others skilled in the art to 10 which it appertains to make and use the same.

This invention has for its object to provide a novel form of support for a mirror, one or more, to be placed upon the shoulders of a person to enable the neck or back of the head 15 to be viewed in a mirror placed in front of the observer, being particularly designed for the use of gentlemen when shaving the back of the neck. It can likewise be used to advantage by ladies and misses when dressing 20 the back hair.

The invention consists of a frame having an upper transverse bar upon which one or more mirrors are hung, a pair of hooks to engage over the shoulders, and a connection 25 for holding the hooks spaced apart the required distance, said connection being preferably adjustable to admit of varying the distance between the hooks to suit different-sized persons.

For a full description of the invention and the merits thereof, and also to acquire a knowledge of the details of construction of the means for effecting the result, reference is to be had to the following description and 30 drawings hereto attached.

While the essential and characteristic features of the invention are necessarily susceptible of modification, still the preferred embodiment of the invention is illustrated in 35 the accompanying drawings, in which—

Figure 1 is a perspective view showing the application of the invention. Fig. 2 is a perspective view of the device. Fig. 3 is a side elevation. Fig. 4 is a modification showing 45 the upper transverse bar of the frame composed of sections.

The same parts are referred to in the following description and indicated in all views of the drawings by like reference characters.

The bracket or support consists, essentially, of a frame comprising an upper transverse

bar 1, braces 2, upwardly-diverged supports 3, shoulder-hooks 4, and a transverse connection 5. The frame, with the exception of the transverse connection 5, is preferably 55 constructed of a single length of stout wire bent into the form substantially as shown, the terminal portions of the wire forming the hooks 4, which are of a size to engage over the shoulders of a person of average size, said 60 hooks being adapted to be bent inward for persons of small stature and outwardly for large-sized persons. The middle portion of the wire forms the transverse bar 1, from which one or more mirrors 6 are suspended. 65 This bar 1 is bent midway of its ends to cause the parts to incline in opposite directions, whereby a pair of mirrors when employed are caused to incline in opposite directions, thereby enabling the person to view the back 70 of the head or neck by reflection in a mirror in front of which the person may be standing. The end portions of the wire comprising the frame are folded upon themselves, as shown at 2, and these folded parts constitute the 75 braces to engage with the back of a person and hold the frame in an upright position. The supports 3 are upwardly diverged, so as to provide a transverse bar 1 of ample length for supporting mirrors of proper size to enable 80 the user to obtain a full view of the back of the head or neck. The mirrors 6 are loosely suspended from the inclined portions of the transverse bar, so as to occupy a vertical position. It is obvious that the mirrors may be 85 attached to the upper portion of the frame in any desired way.

The transverse connection 5 joins the side members of the frame and holds the shoulder-hooks 4 the required distance apart and in 90 the preferable construction is adapted to be lengthened and shortened to admit of varying the distance between the shoulder-hooks to enable the frame to be conveniently fitted to different-sized persons. The outer end portions of the connection 5 are utilized as binders for holding the end portions of the folded parts 2 together, as clearly indicated. The transverse connection consists, preferably, of wire, the outer end portions being bent around 95 the members or parts of the braces 2 to hold them together, as stated. Any means may 100

be employed for admitting of the connection 5 being lengthened and shortened, and, as shown, the connection is composed of sections the inner end portions of which are 5 overlapped and secured in an adjusted position by means of a binder 7, consisting of a slide and a clamp-screw.

The inclination of the end portions of the 10 transverse bar 1 is such as to admit of the back of the neck or head being viewed by reflection in a mirror placed in front of the person, thereby enabling the person to dress and arrange the back hair according to taste without requiring the services of an attendant or 15 meeting with the annoyance and inconvenience attendant upon the use of front and back mirrors propped or supported by means wholly independent of the person.

In the modification shown in Fig. 4 the upper 20 transverse bar 1 of the frame is composed of sections, thereby admitting of the side portions being separated and placed one upon the other when it is required to reduce the frame to a compact form for storing or other 25 desired purposes. By having the bar 1 formed in sections it can be lengthened and shortened similar to the connecting-bar 5, whereby the width of the frame can be varied. A clip 8, similar in construction to the binder 7, is 30 utilized for holding the overlapped parts of the sections together.

Having thus described the invention, what is claimed as new is—

1. A mirror-bracket comprising a mirror-supporting bar bent between its ends to provide oppositely-inclined members, side supports having braces at their lower ends for engagement with the back of the person, forwardly-extending shoulder-hooks arranged about midway of the ends of the said side supports, and an adjustable transverse connection forming a tie for the said side supports, substantially as specified.

2. A mirror-bracket formed of a single length of wire and comprising a transverse 45 mirror-supporting bar having its end portions oppositely inclined, side members having their upper portions upwardly diverged and their lower parts constituting braces for engagement with the back of the person, shoulder-engaging hooks extended forward from the side members at a point intermediate of their ends, and a transverse connection forming a tie for the said side members, substantially as described.

In testimony whereof I affix my signature in presence of two witnesses.

SVERRE SVENDSGAARD. [L.S.]
